VERTICAL TUBE EVAPORATOR

Harold E. Jacoby, Brooklyn, and Charles P. Nilan,
Point Lookout, N. Y., assignors to General
American Transportation Corporation, Chi-
cago, Ill., a corporation of New York

Application February 27, 1946, Serial No. 650,468

6 Claims. (Cl. 159—27)

1

This invention relates to evaporators and more particularly to a novel unitary construction of evaporator body adapted to be incorporated in a multiple effect evaporating system.

A multiple effect evaporator commonly comprises two or more evaporator bodies each of which includes a heating element and a vapor separator chamber, the evaporator bodies being so interconnected that the vapors from one body or effect are fed to the heating element of the next effect. In evaporators of the type with which the present invention is concerned the liquor (i. e., any liquid which is to be evaporated) is heated within a heating element, usually of tubular construction, by transfer of heat from vapors outside the tubes. Movement of the liquor through the tubes is achieved either by maintenance of a suitable hydrostatic head of the liquor or by pumping the liquor through the tubes or by utilizing the thermosiphon action induced by heat transfer from the outside of the tubes to the liquor within the tubes or by a combination of two or more of these methods.

In addition to the evaporator body itself, it is the usual practice to provide a device known as "an entrainment separator" for removing any entrained liquor from the vapors formed in the evaporator. This is commonly done in a separator chamber which drains the separated liquor back to the evaporator. It is also known to provide one or more "flash chambers" through which steam condensate or superheated liquor are passed. In these flash chambers the hot liquor or condensate is exposed to a lower pressure at which its own heat serves to produce spontaneous vaporization or "flashing" of a part of the liquid and thereby to avoid possible waste of such heat. Each one of the evaporating units at different pressures is called an "effect." Since the steam or vapor pressure in successive effects decreases, condensate from any effect except the last effect contains heat that may be converted into steam and used as a heating medium in a successive effect. By causing the steam condensate from one effect to flow into a flash chamber maintained at the lower pressure of another effect, a portion of the condensate vaporizes and may be used as a heating medium in the latter effect. In somewhat similar fashion, in cases where the liquor fed to the evaporator is superheated with respect to the conditions existing in the effect into which the liquor is to be introduced, the liquor may be passed through a liquor flash chamber to permit flash evaporation of a portion thereof.

2

It is an object of the present invention to provide an improved evaporator body construction wherein the evaporator body contains not only the usual heating element and vapor separator chamber but may also contain an entrainment separator or a condensate flash chamber or a liquor flash chamber or any two or all three of these additional elements. By incorporating the entrainment separator and flash chambers in the evaporator body in accordance with the present invention a completely self-contained and self-supporting unit may be achieved. Such a self-contained and self-supporting unit eliminates the necessity of expensive structural steel supports such as have been previously used for supporting the different elements of an evaporator. The work involved in installing an evaporator system and the cost of installation are thus reduced materially, since apart from accessories, such as pipes, pumps and the like only a single unit of the equipment need be handled for each effect that is to be installed. Further the compactness of an evaporator incorporating the present construction reduces the space requirements of the system and enables the evaporator to be installed in a restricted space. The unitary construction of the present invention is also an advantage in shipping the evaporator since fewer parts have to be accounted for. Other objects and advantages of the invention will be in part obvious and in part pointed out hereafter.

Although we are giving below certain specific examples of our invention and its application in practical use and are giving also certain modifications and alternatives, it should be understood that these are not intended to be exhaustive or limiting of the invention. On the contrary, we are giving these as illustrations and are giving herewith explanations in order fully to acquaint others skilled in the art with our invention and the principles thereof and a suitable manner of its application in practical use, so that others skilled in the art may be enabled to modify the invention and to adapt it and apply it in numerous forms each as may be best suited to the requirement of a particular use.

The many objects and advantages of the present construction may best be appreciated by reference to the accompanying drawings which illustrate an evaporator incorporating a preferred embodiment of the invention and wherein:

Figure 1 is a vertical section through the evaporator showing the arrangement of the principal elements within the evaporator body; and

Figure 2 is a diagrammatic illustration of the

manner in which evaporator bodies incorporating the present invention may be interconnected in a multiple effect evaporating system.

Referring to the drawings, and more particularly to Figure 1, the numeral 10 generally designates an evaporator body comprising a cylindrical outer shell or casing 11 that encloses a vapor separator chamber 12, a heating element comprising the tube bundle 14, an entrainment separator chamber 16, a liquor flash chamber 18 and a condensate flash chamber 20. (Relatively few tubes are shown in the tube bundle on the drawing to avoid confusion of lines; but any required number may be used in accord with accepted engineering principles.) This tube bundle 14 comprises a plurality of tubes that are mounted in the usual manner in an upper tube sheet 22 and a lower tube sheet 24. The lower tube sheet 24 is mounted between a flanged condensate receiving section 26 of the evaporator body 10 and a flanged ring 28. Closure of the lower end of casing 11 is provided by a flanged cap section 30 connected to the flanged ring 28 in such manner that it may be easily removed to provide ready access to the tubes of the tube bundle 14. At the upper end of casing 11 a cap 31 is provided that may be removed to permit access to the vapor separator chamber 12 and upper tube sheet 22.

The upper tube sheet 22 is supported by an annular ring 32 fixed to the casing 11. An expansion joint 34 is provided between the tube sheet 22 and supporting ring 32 to permit necessary expansion of the tubes of the tube bundle 14. The tube sheet 22, expansion joint 34 and ring 32 effectively comprise a wall of the vapor separator chamber 12.

Surrounding the upper and central portions of the tube bundle 14 there is a cylindrical partition 36 that is supported from the vertical wall of casing 11 by an upper annular ring 38 and lower annular ring 40. The cylindrical partition 36 and annular ring 38 cooperate with the vertical wall of the casing 11 to define the annular open-topped entrainment separator chamber 16 into which the vapors from a previous effect may be introduced tangentially through a pipe 42. The construction is such that the vapors entering through the pipe 42 are whirled around in the chamber 16 and non-gaseous constituents contained in the vapors are removed. The separated liquor is removed from the chamber 16 through a connection 44 and the vapors that have been freed from entrained liquor flow over the top of the cylindrical partition 36 and thence downwardly in contact with the tubes of tube bundle 14.

As previously pointed out, the liquor to be evaporated may be superheated and it is desirable that a flash chamber be provided for removal of this superheat before subsequent utilization. The annular rings 38 and 40, the lower portion of cylindrical partition 36 and the vertical wall of casing 11 define an enclosed annular liquor flash chamber 18 that may be used for this purpose. Liquor may enter the chamber 18 through a connection 46 and leave the chamber through a connection 48. Within the chamber 18 the pressure is maintained at such a value that a sufficient portion of the entering liquor flashes into steam to de-superheat the liquor. The evolved vapor may be withdrawn through a connection 50 near the top of the chamber 18.

Liquor leaving the chamber 18 through connection 48 may be conducted by a pipe (not 75

shown in Figure 1) to a connection 52 in the flanged ring section 28 of the evaporator body. The liquor thus introduced passes upwardly through the tubes of tube bundle 14 where it is heated by condensation outside the tubes of either steam or vapors from a preceding effect. As the liquor passes through the tubes, and evaporation of the liquor occurs, the velocity of the mixture of liquor and vapor increases, and the vapor-liquor mixture leaving the upper end of the tubes of tube bundle 14 impinges upon a curved baffle plate 54 that is mounted in the path of the vapor-liquor mixture to deflect the mixture downwardly. Separation of the vapor from the liquor in this mixture occurs within the vapor separator chamber 12 and the vapors leave the evaporator body through an outlet connection 56 near the top of the vapor separator chamber. The liquor thus separated may be withdrawn from the vapor separator chamber through a connection 58.

To utilize the superheat that may be present in the condensate from a previous effect a condensate flash chamber 20 is provided near the bottom of body 10. Surrounding the lower portion of tube bundle 14 there is a cylindrical partition 60 that cooperates with the casing wall 11 to define the open-topped annular condensate flash chamber 20. Condensate from a previous effect may enter the chamber 20 through a connection 62 and vapors flashing from the condensate pass over the top of cylindrical partition 60 into contact with the tube bundle 14. The partition 60 forms a baffle that effectively prevents the entering condensate from impinging directly on the tubes of tube bundle 14. De-superheated condensate flows through a hole 64 in the partition 60 thence downward into the condensate receiving section 26 and out of the evaporator body through condensate outlet connection 66.

The vapors entering the evaporator body through the inlet connection 42 normally contain a small proportion of non-condensable vapor that tends to collect in the central and lower portions of the tube bundle 14 and means are provided for removing this non-condensable vapor. Centrally located in the tube bundle 14 there is a tube 68 that extends from the upper tube sheet 22 down through the center of tube bundle 14, through the lower tube sheet 24 and then out through the wall of flanged ring 28. Near its lower end tube 68 is provided with a plurality of holes 70 through which non-condensable vapor that collects in the lower central portion of the tube bundle may pass to the interior of tube 68 and be withdrawn from the evaporator body, e. g., by an ejector or pump or by venting, depending upon the pressure. It is apparent that only the lower portion of tube 68 is effective in withdrawing non-condensable vapors from the evaporator body but it is desirable that the tube 68 extend to the upper tube sheet 22 so that the symmetry of the tube bundle may be preserved and channelling of the steam or vapors avoided. If the tube 68 did not extend upwardly to the upper tube sheet, the resulting opening in the center of the tube bundle would provide a bypass through which steam or hot vapors might flow without coming in contact with the heating surfaces of the tube bundle. This feature of the present evaporator is described more fully in co-pending application Serial No. 712,810 filed on November 29, 1946.

The evaporator body 10 may be supported in any suitable manner. In the present embodiment the casing 11 and its associated structure

is supported on a cylindrical skirt 72 that is fixed to the casing in any suitable manner, such as by welding, and extends from the bottom of the casing to the floor or other structure on which the evaporator body is mounted. An opening 74 is provided in the skirt 72 to permit access to the lower portion of the evaporator body. It is apparent that other supporting means such as structural steel legs in the form of T-beams or I-beams may be used in place of the skirt 72.

The evaporator of the present invention is particularly adapted for use in multiple effect evaporating systems and the manner in which a number of evaporator bodies incorporating the present invention can be interconnected in a multiple effect system is illustrated diagrammatically in Figure 2 of the drawings. Referring to Figure 2, the numerals 100, 102 and 104 designate the several evaporator effects having bodies 10a and 10b generally similar to the evaporator body 10 shown in Figure 1. Superheated liquor to be evaporated is fed to the liquor flash chamber 18a of evaporator body 10c of the final effect 104 through a pipe 106, and the superheat removed by partial vaporization of the liquor. From the liquor flash chamber of body 10c the liquor flows through pipe 108 to the bottom of the evaporator body 10c, enters the evaporator body through the connection 52a and then flows up through the tube bundle of this evaporator body to the vapor separator chamber 12c wherein the liquor and associated vapor are separated. The liquor leaves the evaporator body 10c through pipe 110 and is transferred by means of transfer pump 112 and pipe 114 to the bottom of evaporator body 10b of the effect 102.

Since the liquor at this stage contains no superheat it is unnecessary that the evaporator body 10b be provided with a liquor flash chamber. The entering liquor passes up through the tube bundle in the evaporator body 10b of effect 102, the portion of the liquor vaporized within the tubes being separated from the liquor in its vapor separator chamber 12b. The separated liquor leaves body 10b through pipe 110a and is transferred by transfer pump 112a and pipe 114a to the bottom of the evaporator body 10a of the first effect 100.

A further quantity of the liquor is vaporized within the tubes of evaporator body 10a and the resulting vapor-liquor mixture is separated in its vapor separator chamber 12a. Concentrated liquor leaves the body 10a through the outlet pipe 122.

Vapors from the vapor separator chamber 12a of body 10a are conducted through a vapor pipe 124 to the entrainment separator 16b of the body 10b wherein entrained liquor is separated from the vapors. These vapors pass over the rim of the cylindrical baffle 36b into contact with the tube bundle in the body 10b and the separated liquor flows through pipe 121 into the concentrated liquor pipe 122.

Vapors from the vapor separator chamber 12b of the body 10b are conducted through a pipe 124a to the entrainment separator of body 10c of the next effect 104 where entrained liquor is separated from these vapors in the same manner as before. The vapors then pass into contact with the tube bundle of body 10c and the separated liquor is withdrawn through pipe 121a and flows into pipe 110a and thence through pump 112a and pipe 114 to the bottom of body 10a.

Vapors from the vapor separator chamber of

the body 10c pass through a tangential vane, or other conventional, entrainment separator 130 on the top of body 10c and thence through vapor pipe 132 to a barometric or other condenser (not shown).

Vapors evolved in the liquor flash chamber 18a of the body 10c are removed near the top of the liquor flash chamber and pass through pipe 134 to the separating chamber 12c or directly to the vapor pipe 132. If desired, a pressure differential may be maintained by a restriction or check valve (not shown) in the connecting pipe 134.

Steam is supplied to the system and particularly to evaporator body 10a through a steam inlet pipe 136. The steam flows into contact with the tube bundle of body 10a and is condensed on the outer surface of the tubes, the condensate being collected near the bottom of the body 10a and removed through pipe 138. Since the condensate in the first effect is free from contaminants that are sometimes present in the vapor of the liquor being evaporated, it is desirable that the condensate from the first effect be segregated and not passed on to a subsequent effect where it would mix with other vapor condensate. Any condensate collecting in the chamber 18a may be drained off through outlet 44a or an internal opening may be provided through flange 38a to drain the condensate to the bottom of the tube bundle where it is drawn off from outlet 66 through pipe 138.

The condensate collecting at the bottom of evaporator body 10b of effect 102 is transferred through pipe 140 to the condensate flash chamber of body 10c. Since the steam spaces 14 and 16 of later effects, such as 104, are normally maintained at lower pressure than the corresponding space in preceding effects (in the triple effect evaporator shown), a portion of the condensate entering the condensate flash chamber 20 of the third effect 104 will vaporize and pass into contact with its tube bundle. The unvaporized condensate flows to the bottom of the body 10c where it mixes with condensate from the tube bundle of that body and the mixed condensate is withdrawn through a pipe 142 by a condensate transfer pump 144.

From the foregoing description it is apparent that an evaporator body constructed in accordance with the present invention may be effectively incorporated in a multiple effect evaporating system to provide a number of important advantages over previously proposed constructions. The principal evaporator elements of each effect are so combined in a compact unitary structure as to provide a self-contained, self-supporting unit that may be conveniently handled during installation. The self-supporting feature eliminates the necessity for special structural steel supports and the expense incident to the erection of such supports. This self-supporting feature is particularly advantageous where the evaporator is to be installed outside of a building and no building structure is available for supporting the evaporator unit or units. The arrangement of the entrainment separator and flash chambers in the form of annular chambers surrounding the tube bundle results in efficient utilization of the available space within the evaporator body and desired vapor flow parallel to the tubes of the tube bundle.

Further, the present construction provides flexibility in manufacture. Thus each of the chambers located adjacent the tube bundle, i. e., the entrainment separator, the liquor flash chamber

and the condensate flash chamber may be omitted from or incorporated in a particular evaporator body with special advantages as desired but without interfering with the essentially self-contained and self-supporting character of the structure. If desired different portions of the evaporator unit, such as the vapor separator chamber, may be separately fabricated and connected by flanges or in another suitable manner to facilitate shipment and erection.

We claim:

1. A unitary evaporator body adapted to be used in a multiple effect evaporating system for evaporating one or more components of a solution, said evaporator body comprising upper and lower spaced tube sheets, a plurality of tubes mounted at their ends in said tube sheets to form a tube bundle, a casing substantially enclosing said tube bundle, said casing extending substantially above said upper tube sheet and having a closed upper end that defines with the upper portion of the casing and the upper tube sheet a vapor separator chamber, cylindrical wall means surrounding said tube bundle and positioned close thereto, an annular partition extending from said wall means to said casing and defining with said wall means and casing an annular entrainment separator chamber surrounding said tube bundle, said separator chamber being open at its top to communicate with the tubes of said tube bundle, a tangential inlet connection formed in that portion of the casing that constitutes the outer wall of said annular chamber and through which a fluid mixture may be tangentially introduced into said chamber for separation, and an outlet connection formed in said casing near the bottom of said chamber for removal of separated liquid from said separator chamber and evaporator body, the diameter of the portion of said casing that partially defines said annular chamber being sufficiently greater than the diameter of said wall means to provide an efficient separating space in said separator chamber.

2. A unitary evaporator body adapted to be used in a multiple effect evaporating system for evaporating one or more components of a solution, said evaporator body comprising upper and lower spaced tube sheets, a plurality of tubes mounted at their ends in said tube sheets to form a tube bundle, a casing substantially enclosing said tube bundle, said casing extending substantially above said upper tube sheet and having a closed upper end that defines with the upper portion of the casing and the upper tube sheet a vapor separator chamber, cylindrical wall means surrounding said tube bundle and positioned close thereto, a first annular partition extending from said wall means to said casing and defining with said wall means and casing a first annular separator chamber surrounding said tube bundle, said separator chamber being open at its top to communicate with the tubes of said tube bundle, a tangential inlet connection formed in that portion of the casing that constitutes the outer wall of said annular chamber and through which a fluid mixture may be tangentially introduced into said first chamber for separation, an outlet connection formed in said casing near the bottom of said first annular chamber for removal of separated liquid from said first annular chamber and evaporator body, a second partition between said wall means and casing below said first partition and defining with said first partition casing and wall means a second annular

chamber, said second annular chamber being provided with an inlet connection and a pair of outlet connections formed in that portion of said casing that constitutes the outer wall of said second annular chamber, one of said pair of outlet connections being located near the top of said second chamber and the other being located near the bottom of said second chamber, and the diameter of the portion of said casing partially defining said two annular chambers being sufficiently greater than the diameter of said wall means to provide an efficient separating space in said annular separator chambers.

3. A unitary evaporator body adapted to be used in a multiple effect evaporating system for evaporating one or more components of a solution, said evaporator body comprising upper and lower spaced tube sheets, a plurality of tubes mounted at their ends in said tube sheets to form a tube bundle, a casing substantially enclosing said tube bundle, said casing extending substantially above said upper tube sheet and having a closed upper end that defines with the upper portion of the casing and the upper tube sheet a vapor separator chamber, a first cylindrical wall member surrounding said tube bundle and positioned close thereto, an annular partition extending from said wall member to said casing and defining with said first wall member and casing an annular entrainment separator chamber surrounding said tube bundle, said separator chamber being open at its top to communicate with the tubes of said tube bundle, a tangential inlet connection formed in the portion of the casing that constitutes the outer wall of said first annular chamber and through which a fluid mixture may be tangentially introduced into said chamber for separation, an outlet connection formed in said casing near the bottom of said chamber for removal of separated liquid from said first annular chamber and evaporator body, a second annular wall member positioned below said first wall member and cooperating with said casing to define a second annular chamber surrounding said tube bundle and open at its top to communicate with tubes of said tube bundle, said second annular chamber having an inlet connection formed in its outer wall and a drain connection near the bottom thereof for removal of separated liquid, the diameter of that portion of said casing defining said first and second annular chambers being sufficiently greater than the diameter of said wall members to provide an efficient separating space in said two annular chambers.

4. A unitary evaporator body adapted to be used in a multiple effect evaporating system for evaporating one or more components of a solution, said evaporator body comprising upper and lower spaced tube sheets, a plurality of tubes mounted at their ends in said tube sheets to form a tube bundle, a casing substantially enclosing said tube bundle, said casing extending substantially above said upper tube sheet and having a closed upper end that defines with the upper portion of said casing and the upper tube sheet a vapor separator chamber, cylindrical wall means surrounding said tube bundle and positioned close thereto, and a plurality of annular partitions extending from said wall means to said casing and defining with said wall means and said casing three vertically spaced annular separator chambers surrounding said tube bundle, each of said annular chambers being provided with an inlet connection formed in said casing for admission of a fluid mixture to the chamber,

a first outlet near the top of said chamber for removal of separated vapor therefrom and a second outlet near the bottom of said chamber for removal of separated liquid therefrom.

5. An evaporator body according to claim 4 and wherein the upper and lower of said three annular chambers are open at the top to communicate with the tubes of said tube bundle, the uppermost of said three annular chambers is provided with a tangential inlet connection, and the diameter of said casing is uniform throughout its height.

6. A unitary evaporator body adapted to be used in a multiple effect evaporating system for evaporating one or more components of a solution, said evaporator body comprising upper and lower spaced tube sheets, a plurality of tubes mounted at their ends in said tube sheets to form a tube bundle, a vertical cylindrical casing having a uniform diameter substantially greater than the diameter of said tube bundle and substantially enclosing said tube bundle, said cylindrical casing extending substantially above said upper tube sheet and having a closed upper end that defines with the upper portion of the casing and the upper tube sheet a vapor separator chamber, cylindrical wall means surrounding said tube bundle and positioned close thereto, an annular partition extending from said wall means to said

casing and defining with said wall means and casing an annular separator chamber surrounding said tube bundle, said separator chamber being open at its top to communicate with the tubes of said tube bundle, a tangential inlet connection formed in the portion of said casing that forms the outer wall of said annular chamber and through which a fluid mixture may be introduced into said chamber for separation, and an outlet connection formed in said casing near the bottom of said annular chamber for removal of separated liquid therefrom, the diameter of said casing being sufficiently greater than the diameter of said wall means to provide an efficient separating space in said separator chamber.
